UNITED STATES PATENT OFFICE.

HOWARD E. CHAMBERS AND JOHN L. DOWNING, OF SEATTLE, WASHINGTON.

CAMP STOVE.

1,403,842.

Specification of Letters Patent. Patented Jan. 17, 1922.

Application filed July 31, 1920. Serial No. 400,335.

To all whom it may concern:

Be it known that we, HOWARD E. CHAMBERS and JOHN L. DOWNING, citizens of the United States, and residing at Seattle, in 5 the county of King and State of Washington, have invented certain new and useful Improvements in Camp Stoves, of which the following is a specification.

This invention relates to an improvement 10 in portable stoves, of the type designed for use in camping or the like, the construction permitting the stove to be folded into a small compact shape for storage.

The improved stove is made up of a top, 15 side sections hinged thereto, and legs having hinged connection with the top, the side sections being capable of use as top extensions or as shields to properly direct the draft to the stove.

20 The invention in the preferred form of details will be described in the following specification, reference being had particularly to the accompanying drawings in which:—

25 Fig. 1 is a view in elevation of the improved stove, showing the parts in position for use.

Fig. 2 is a similar view of the stove folded.

The improved stove comprises a top section 30 1, of appropriate size and including a rectangular frame 2. Rods 4 connect the ends of the frame and pass through the brace strip, thus providing an open grate-like top. The respective corners of the

35 frame forming the top are provided with pins to which are hinged legs 6. These legs are pointed at 7 at their free ends, so that the stove as a whole may be supported by forcing the free ends of the legs into the 40 ground. Certain of the legs are offset at 8 for a portion of their length in order to permit folding of the respective legs towards each other in flat relation to the top without interference. The legs at one end of the

45 grate have a plate 5 secured thereto, which cooperates with the side plates to control draft to the fire, and also to serve as a protection to prevent the flames from shooting out through the end, so that one may approach the grate to handle the utensils without danger of having their clothes set 50 on fire.

Side plates 9, preferably imperforate have hinged connection at 10 with the side bars of the top frame, the free side edges of these 55 plates having skeleton legs or supports 11, adapted to be extended to support the plates, or to be folded flat against the plates when desired.

In the use of the stove it is set up by moving the legs at right angles to the top and forcing said legs partially into the ground. The fire may then be built beneath the top section, and the cooking utensils placed on said top section to be heated. Either or 65 both of the side plates may be extended and supported to serve as auxiliary top sections for the stove, or either of said side plates may be turned downwardly at an appropriate angle with the top section, or so as to 70 completely cut off air admission from either side or both sides of the top section. The draft may be thus controlled by the adjustment of these side plates, for the more effective burning of the fuel. 75

The folding of the stove is obvious, the legs being folded into contact with the bottom of the top section, one of the side plates folded on top of the top section and the other on the bottom, or both on the bottom 80 as the hinged construction may provide, thus forming a compact small package which may be readily handled through a handle 12 secured to one of the side bars of the frame of the top section. 85

Claim:

A portable folding stove comprising a grid, legs at one end of the grid, a guard plate secured to said legs, legs at the opposite end of the grid, the lower portion of said latter legs being arranged in a plane offset from and inwardly of the upper portion of the legs, imperforate plates secured to the side edges of the grid and having supports connected at their free edges, the supports 95 having a height less than the width of the plates so that said supports may be folded inwardly against the bottom of the plates.

In testimony whereof we affix our signatures.

HOWARD E. CHAMBERS.
JOHN L. DOWNING.
